UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,255,571.

Specification of Letters Patent.

Patented Feb. 5, 1918.

Application filed October 11, 1913. Serial No. 794,596.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to which it 10 appertains to make and use the same.

This invention relates to typewriting machines, and with regard to certain more specific features thereof, to a mechanism for controlling a certain class of movements of 15 the carriage.

One of the objects of the present invention is to provide a simple and practical arrangement of parts so inter-related and co-acting one with another as to produce a com- 20 bined tabulating, line-locking and marginal release mechanism which will be durable in construction and efficient in action. Another object is to provide a mechanism of the above character peculiarly applicable to a noiselessly operating typewriting machine. A further object is to provide a mechanism of the first above-mentioned character in which the parts are so mounted as to permit ease and freedom of movement. A further 25 object is to provide a mechanism of the above character which will be cheap to manufacture and easy to assemble.

Other objects will be in part obvious and in part pointed out hereinafter.

35 The invention accordingly consists in the features of construction, combinations of elements and arrangement of parts which will be exemplified in the construction herein-after set forth, and the scope of the application 40 of which will be indicated in the following claims.

In the accompanying drawings, wherein is shown one of various possible embodiments of this invention,—

45 Figure 1 is a side elevation, partly in section, of the complete mechanism and such as associated and coacting parts of a typewriting machine as are necessary to understand the same;

50 Fig. 2 is a perspective detail view of a connection common to several features of the mechanism;

Fig. 3 is a sectional plan view of the parts shown in Fig. 1;

Fig. 4 is a sectional plan detail view with 55 a portion of the escapement mechanism;

Fig. 5 is a semi-diagrammatic sectional elevation of the tabulating mechanism in normal position and the margin release mechanism in actuated position; 60

Fig. 6 is a similar view of the parts re-versed, that is, tabulator in actuated position and the margin release in up position;

Fig. 7 is an elevational detail view of the tabulating key lever; 65

Fig. 8 is a rear elevation of a portion of the tabulating mechanism;

Fig. 9 is a sectional elevational view of the line-locking mechanism, certain parts being removed for the sake of clearness; and 70

Fig. 10 is a detail sectional view of one end of the rack.

The present invention is illustrated in the accompanying drawings and will hereinafter be described with relation to a Noiseless 75 typewriting machine, for use in which it is peculiarly designed, although it is to be understood that the invention as a whole, and many of its component parts, are applicable to other forms of typewriting machines as 80 well. The Noiseless typewriting machine, like other forms of practical machines on the market, comprises a horizontally reciprocating carriage having an intermittent letter-feed movement from right to left past a 85 common printing point for all of the type which are actuated by suitable finger-con-trolled means in the key-board of the ma-chine. In the operation of the machine it is often desirable to move the carriage rapidly 90 a predetermined distance from right to left, as when tabulating or writing figures in col-umns, for example, and also, when using the machine in the usual manner, it is desirable to provide means for line-locking the key-board to prevent further operations when printing in the right-hand margin of the paper. The line-locking operation, as is 95 well known, usually goes into effect several letter spaces prior to the right-hand mar-gin, in order that an operator may have suffi-cient room to add the completing letters of the word, or to hyphenate the word properly, if it is impossible to complete the same on 100 that line. These features, which, in their 105 broad aspect, are common to many forms of commercial machines, are usually separate and independent mechanisms, each complete

in its own way and operating independently of the other. The present invention, however, as will appear from the following detailed description, comprises a single self-contained structure having certain parts common to all mechanisms, compactly arranged, and so inter-related and coacting with adjacent parts of other mechanisms as to constitute a single unitary invention.

Referring to the drawings in detail, and more particularly to Figs. 1 and 3, in which similar reference characters denote corresponding parts in these and the other views, the mechanisms are shown in a normal position. The carriage 1 carrying the platen roller 2 is adapted to reciprocate along a horizontally disposed shift rail 3 in the usual manner under the intermittent action of the escapement mechanism 4 coacting with an escapement wheel 5 mounted upon an intervening shaft 6 having a rack and pinion connection 7 with the lower part of the carriage. Adjustably mounted upon a rail 9 at the rear of the carriage in such manner as to be moved manually to any position desired, are a plurality of stops, only two of which are herein shown, one being a tabulator stop 8 and the other the right-hand marginal or line-locking stop 10. These stops are adapted to coact with a movable stop 11 centrally disposed in the rear of the machine. In normal position, as shown, the movable stop 11 clears the tabulator stop 8 but will engage the margin or line-lock stop 10 to line-lock the keys, and in order to clear the margin stop to permit writing of additional characters as above explained, the stop 11 is thrown backward on depression of a margin release key 12 in the keyboard of the machine, as will be hereinafter more fully described in detail in the subsequent discussion of the line-locking feature of the mechanism. When the machine is used for tabulating or column space work, this stop is thrown forward into the position shown in Fig. 6 by the tabulating key 13, in which position only it is adapted to coact with the tabulator stop 8. The movable stop 11, which, for convenience, will be hereinafter termed the "margin release lever", is carried in a rearwardly extending centrally disposed abutment 14 adjustable fore and aft of the machine for moving the platen relatively to the normal printing position and holding it rigidly against further rearward movement under the powerful action exerted by the pressure-operating type carriers. This margin release lever has, at its lower end, an offset portion 15 adapted to be pivotally mounted on a pivot screw 16 secured by a nut 17 on the upper side of a trunnion block 18. This compound or universal pivotal mounting of the margin release lever is for the purpose of allowing a lateral movement

of the lever to actuate the line-lock and a fore and aft movement to release the line-lock, as will be hereinafter more fully described. The trunnion block 18 is carried on the end of a horizontally disposed transverse shaft 20, suitably supported in brackets 21, to which shaft it is clamped by suitable screws 22, the block being slotted for a portion of its length to permit a more efficient clamping action. The opposite end of this shaft 20 is bent to one side for engagement with the slotted end 23 of the margin release key lever 24, which is pivotally mounted on a suitable pivot screw 25 in the frame of the machine. The margin release key lever extends forward to the keyboard of the machine and is provided at one end with the key 12 placed near the front and relatively low in the keyboard in order to prevent accidental operation thereof, and a return spring 19 operating near its other end.

As used in connection with the tabulator feature of the mechanism, the margin release lever 11, instead of being rotated backward to clear the margin stop, is moved forward into the position shown in Fig. 6, in which position it will engage and coact with the tabulator stop 8. This forward movement of the margin release lever 11 is obtained by a depression of the tabulator key 13 in the keyboard of the machine, which is mounted upon a short key lever 26, as shown in Fig. 7, pivotally mounted upon a bracket 27 attached to the frame of the machine by a pivot screw 28. The normal, inactive position of the tabulator key lever is secured by a vertically disposed coil spring 30 engaging the lower part 31 of a downwardly projecting arm of the tabulator key, as shown in Fig. 7. This arm is also provided with a forwardly extending point 32 which is adapted to engage the base of the bracket on which the lever is mounted, thus holding the lever in normal raised position. The ear 31 to which the upper end of the spring is connected is disposed to pass under the margin release lever and engage therewith when the tabulator key is depressed, as shown in Fig. 6. The engagement of the ear on the underside of the margin release key lever 24 rotates the latter, thus raising its front end and depressing the forked end 23, thereby causing the margin release lever 11 to rotate inward to the position shown in Fig. 6 ready for engagement with the tabulator stop 8 carried by the carriage. At the same time the fixed or holding dog of the escapement mechanism 4 is disengaged from the escapement wheel 5 and the carriage is allowed to run freely until the stop 8 brings it to rest by engagement with the coacting movable stop 11. It will also be noted that the tabulator key lever is provided with an upper laterally extending

ear 33 passing over the margin release key lever 24 and forming an up stop therefor.

Pivottally connected to the lower part of the tabulator key lever 26 at the point 34 is a rearwardly extending link 35 having its rear end pivottally connected to one end of a crank arm 36 mounted on a second transversely disposed shaft 37 pivotally mounted in suitable brackets 38 attached to the frame 16 of the machine. This shaft is preferably made of square stock to admit of simple construction of the arms which are attached thereto, one of these arms being the crank arm 36 above mentioned.

15 On the transverse shaft 37, at the opposite end thereof, is a downwardly extending arm 40, the lower end of which is adapted to engage the tail end of the holding or fixed escapement dog in order to disengage this 20 dog from the escapement wheel when the tabulator key is depressed, thereby permitting a free movement of the carriage until arrested by the tabulator stop.

In order to prevent excessively rapid 25 movement of the carriage when the holding dog is thrown out, there is provided on the escapement shaft a brake disk 41 adapted to be engaged by a friction brake 42. Mounted upon the escapement bracket 43 by a pivot 30 screw 44, as is perhaps more clearly shown in Figs. 4 and 8, is a lever 45 carrying near its center the brake shoe 42. The position of this lever is controlled by an adjusting screw and nut 46 which normally keeps the 35 shoe just out of engagement with the disk 41, being allowed to move into engagement therewith when the transverse shaft 37 is rotated to move the holding dog out of engagement with the escapement wheel. The 40 braking pressure exerted on the disk by the brake shoe is controlled by a spring 47 mounted upon the lever 45, the tension of which is adjustably controlled by a suitable screw and check nut 48. It will be seen that 45 this mechanism provides a construction in which the action of the brake is independent of the degree of pressure which may be brought to bear upon the tabulator key, since the braking action is solely dependent on the 50 action of the actuating spring. When the tabulator key is released the parts are all returned to normal position under the action of the tabulator spring 30 directly connected therewith.

55 Taking up the line-lock and margin release features of this mechanism now more in detail, the margin release lever 11 has connected therewith, at its lower part, a laterally projecting ear 50 to which one end of a coiled return spring 51 is secured, the opposite end being attached to a pin 52 on the trunnion block 18. This spring is for the purpose of holding the margin release lever in its normal position to be engaged by the margin stop at the end of the printing line.

Also attached to the margin release lever 11 adjacent this ear is a laterally extending bent arm 53 having an upturned end to which is connected an adjustable pull wire 54 extending fore and aft of the machine to a line-lock bail 55 which is pivottally mounted at its ends in suitable brackets 56 attached to the frame of the machine. The outer end of the pull wire passes through a relatively large hole in an ear 57 on the line-lock bail 75 resting against a suitable transverse pin 58 in the pull wire. The bail is retained in that position by the action of a coil spring 60 about the pull wire, the tension of which may be regulated by an adjusting nut 61 80 held in adjusted position by an outer check nut 62.

The purpose of the spring is to permit temporary disengagement of the line-lock bail from the key levers 59 after the same 85 have been locked in case one key lever is in depressed condition at the moment when the line-lock bail comes into action, in which case, upon upward movement of the depressed key lever, the bail is pushed forwardly by the key lever, after which it is brought back into locking position by action of the coil spring 60. It is to be noted that this bail acts relatively close to the point of application of power on the keys, thereby 95 eliminating, as much as possible, action of certain power multiplying devices intervening between the key and lock as might otherwise occur.

It will thus be seen that when the margin 100 stop 10 engages the margin release lever 11 a continued movement of the carriage rotates the lever on its vertical pivot 16 to carry the arm 53 rearward and exert a pull on the pull wire 54 to allow the line-lock bail to 105 drop under the upper hook portions 63 of the key levers. This movement prevents any further downward movement of any of the key levers until the margin release lever 11 has been actuated by depression of the margin release key 12 in the keyboard, as above 110 explained.

The tabulating and line-locking stops, while shown in some of the figures more or less diagrammatically, are shown more in 115 detail in Figs. 1 and 3, and they with their supporting means are particularly designed to have a certain coercive relation with the tabulating and line-locking mechanism above described. Referring more particularly to Fig. 1, the body portion of the stop 10, for example, is provided with a relatively long cylindrical sleeve 65 which is adapted to slide along the rail 9 without binding or cramping. This rail 9 is supported from a 125 web 66 secured to the carriage in any desired manner, and is provided with a plurality of vertically disposed notches or teeth 67 with which the teeth on the lower end of a latch 68 are adapted to coact under the action of 130

a coil spring 70. The upper end of the latch is provided with an operating handle 71 and a raised indicator 72 lying flush with a depressed paper scale 73 carried at the upper rear portion of the paper table 74. By having the indicator and scale lying flush with each other and with the surface of the paper table all projections with which the edge of the paper might engage after being fed 10 around the platen roller are eliminated. A more accurate reading of the scale is also permitted, as the index and indices of the scale are more closely adjacent one another.

Aside from the usual adjustability of 15 these stops, as may be desired when using different sizes of paper, for example, the rack 9 upon which the stops are mounted is also adjustable on its supporting web in order to bring the stops into correct relative 20 position with the printing point, admitting of a full letter-space of the carriage just previous to the action of the stop for line-locking purposes. From the enlarged detail view, Fig. 10, of one end of the rack, it 25 will be noted that the web 66 is provided with an extension 75 which is engaged by a recessed nut 76 threaded on the end of the rack 9. This nut has two functions, the first being to hold the rack down upon the 30 web 66 by engaging the projection 75, and the second, to admit of longitudinal adjustment of the rack on the web. After adjusting the nut 76 a check nut 77 is brought 35 against the same to lock the parts in adjusted position. The nut 77 may be slotted for the reception of a screw driver and suitably knurled for ease of adjustment and appearance. While only one end of the rack is here shown, it is of course to be understood that 40 the opposite end is provided with a similar adjusting mechanism. Thus as one nut 76 is turned in one direction to move the rack, the opposite nut may be turned in the opposite direction to take up the adjustment.

45 Coöoperating with the adjustability of the rack, as above described, is a second adjustment associated with the margin release lever 11, which is also designed to accomplish certain other functions, as will hereinafter appear clear. This second adjustment is mounted on the center tie or rear abutment 14 carrying the margin release lever 11. Passing through one side portion 50 of the rear abutment 14 is an adjusting screw and lock nut 80 adapted to limit the lateral movement of the margin release lever in the direction of movement of the carriage when a tabulating key is depressed; that is, when the carriage is running free, on release of 55 the escapement, from one column to another. On depressing the tabulator key the margin release lever 11 oscillates forward into the path of travel of the tabulator stop 8 which contacts therewith, thus moving the margin 60 release lever 11 into contact with the round-

ed point of the adjusting screw 80. A cavity or depressed cam surface 81 in the margin release lever 11 receives the point of the screw 80, so that when the tabulating key is released and allowed to return to its normal position, the tension of the carriage under the action of its carriage drive mechanism against the margin release lever will tend to force the margin release lever rearward, thus assisting in withdrawing the release 75 lever from the path of the tabulator stops. If the tension of the carriage drive mechanism is abnormally high, the present construction would make the release and return of the mechanism to normal position just as 80 rapid as though a low tension were used. It will readily be understood that the greater pressure on the angle of the cavity 81 presented to the point of the screw 80 would increase the tendency of the angle to force 85 the release lever rearwardly and thus offset the increase in friction or binding, due to the increased tension of the carriage. If the angle of the side of the cavity which contacts with the screw 80 were made sufficiently 90 acute, the operation would be substantially automatic. As the tabulator stop forces the release lever into contact with the screw the release lever itself will be forced rearwardly out of the path of the tabulator stop. By 95 adjusting the screw 80 in either direction the point at which the margin release lever will arrest the movement of the carriage can be controlled independent of the margin stop.

100 It will thus be seen that this mechanism is adapted to prevent binding and permits a rapid operation of the various parts to normal position. It also provides means for adjusting the margin release lever to compensate for any irregularities or inaccuracies which may exist between the margin stop and the tabulator stops, inasmuch as they both coact with a common lever. In adjusting the carriage stops it is customary to adjust the margin stop 10 first, this adjustment being secured through the adjustment of the margin stop rack shown in Fig. 10 and above described, and by means of this separate adjustment the proper movement of 105 the margin release lever coacting therewith is properly regulated.

110 The operation of this device should be obvious from the above disclosure, although a brief description thereof is as follows:

115 As shown in Fig. 3, the carriage 1 has reached a letter-space position where an actuation of any type action will cause the margin stop 10 to engage and move the margin release lever 11 at the rear of the machine. Any lateral movement of this release lever will exert a pivotal action independently of the trunnion block to swing the free or outer end of the transverse arm 120 125 rearward, causing the line-locking bail 130

to move under the outer hook portions of the key levers. This will, of course, prevent any downward movement of any of the key levers until the margin release key 12 in the keyboard of the machine has been depressed to rotate the transverse shaft 20 and trunnion block 18 bodily about a substantially horizontal axis to carry the margin release lever 11 rearward out of the path of travel of the line-locking or marginal stop 10. This will release the line-lock bail and permit additional characters to be printed to complete the word or hyphenate it properly before going on to the next printing line. When tabulating or column-spacing the machine, substantially the same parts are operated, although they are operated in an opposite or reverse manner. For example, assuming the carriage 1 to be at the extreme right-hand or line-spacing position, the tabulating key is depressed, which, as shown in Fig. 6, will cause a reverse or upward movement of the margin release lever 24 to swing the trunnion block 18 in a corresponding opposite direction and carry the margin release lever 11 at the rear of the machine into the path of travel of the tabulating stop 8. This same downward movement of the tabulating key will, through the link 35 and arm 36, force the holding dog out of engagement with the escapement wheel 5, as shown in Fig. 6, allowing the wheel and escapement shaft to run freely. The carriage is then drawn toward the left under the action of the usual carriage drive spring until the tabulating stop 8 coacts with the margin release lever 11 in its forward position and arrests the carriage. In order to prevent too rapid movement of the carriage when the escapement is released the brake shoe 42 is applied to the brake disk 41 carried by an escapement shaft to retard the movement thereof, as above explained. The degree of retardation is entirely independent of the pressure exerted on the tabulator key 13, thus insuring as rapid a movement of the carriage as is consistent with the most efficient operation.

It is thus seen that this invention provides a simple and practical arrangement of the parts compactly positioned, adapted to control some or a certain class of the movements of the carriage. The parts are cheap to manufacture and easy to assemble, and the invention is believed to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings

shall be interpreted as illustrative and not in a limiting sense.

Having described my invention, what I claim as new and desire to secure by Letters Patent is:

1. In a typewriting machine, in combination, a carriage, a key, a stop movable by said carriage about a vertical axis, and by said key about a transverse axis, key levers, and a line lock member for the latter having a permanent connection with said stop and movable thereby but only when said stop is moved by said carriage.

2. In a typewriting machine, in combination, a carriage, a stop therefor having a limited movement thereby, key levers, a line lock member for the latter movable at substantially right angles to the movement of said stop by said carriage, and operative connecting means between said member and said stop including a bell crank lever having a resilient connection with said member.

3. In a typewriting machine, in combination, a margin stop, a tabulator stop, and a third stop adapted normally to coact with said margin stop but being movable about a horizontal axis into position to coöperate with the tabulator stop and being movable about a substantially vertical axis to cause line locking of the keys.

4. In a typewriting machine, in combination, a margin stop, a tabulator stop, a movable stop coöperative with said stops, means normally holding the movable stop in the path of the margin stop, a release key lever whereby said movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop.

5. In a typewriting machine, in combination, a margin stop, a tabulator stop, a movable stop coöperative with said stops, means normally holding the movable stop in the path of the margin stop, a release key lever whereby said movable stop may be moved about a horizontal axis out of the path of travel of said margin stop, another key lever whereby the movable stop may be moved about the same axis into the path of the tabulator stop, means permitting a movement of said movable stop about a vertical axis when engaged by the tabulator stop, and a line lock device rendered effective by the last said movement.

6. In a typewriting machine, in combination, a margin stop, a tabulator stop, a movable stop coöperative with said stops, means normally holding the movable stop in the path of the margin stop, a release key lever

- 6 whereby said movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop or the margin stop.
- 10 7. In a typewriting machine, in combination, a margin stop, a tabulator stop, a movable stop coöperative with said stops, means normally holding the movable stop in the path of the margin stop, a release key lever whereby said movable stop may be moved about a horizontal axis out of the path of travel of said margin stop, another key lever whereby the movable stop may be moved about the same axis into the path of the tabulator stop, means permitting a movement of said movable stop about a vertical axis when engaged by the tabulator stop or the margin stop, and a line lock device rendered effective by the last said movement.
- 15 8. In a typewriting machine, in combination, a margin stop, a tabulator stop, a movable stop coöperative with said stops, means normally holding the movable stop in the path of the margin stop, a release key lever whereby said movable stop may be moved about a horizontal axis out of the path of travel of said margin stop, another key lever adapted to act through the first said lever whereby the movable stop may be moved about the same axis into the path of the tabulator stop, and means permitting a movement of said movable stop about a vertical axis when engaged by the tabulator stop.
- 20 9. In a typewriting machine, in combination, a margin stop, a tabulator stop, a movable stop coöperative with said stops, means normally holding the movable stop in the path of the margin stop, a release key lever whereby said movable stop may be moved about a horizontal axis out of the path of travel of said margin stop, another key lever whereby the movable stop may be moved about the same axis into the path of the tabulator stop, means permitting a movement of said movable stop about a vertical axis when engaged by the tabulator stop.
- 25 10. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means connected with said second mentioned key lever whereby the step-by-step escapement of the machine is thrown out.
- 30 11. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop, and means connected with said second mentioned key lever whereby the step-by-step escapement of the machine is thrown out and a carriage retarding device is operated.
- 35 12. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop, and a carriage stop device comprising, in combination, a block, a lever pivotally mounted thereon, a rock shaft fixed to said block and having an axis of movement transversely of the axis of movement of said pivoted lever, and a spring normally urging said lever relatively to said block.
- 40 13. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop, and a carriage carrying marginal and tabulating stops, a coacting movable stop on the frame of the machine, tabulating and margin release key levers, both connected with said stop, said tabulating and margin release key levers being pivoted at different points, one being adapted to act on the other to produce a movement of the other opposite to its normal movement, one of said levers being in the form of a bell crank lever, and a connection between the end of one arm and the escapement mechanism for throwing out the escapement mechanism when depressed.
- 45 14. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop, and a carriage carrying marginal and tabulating stops, a coacting movable stop on the frame of the machine, tabulating and margin release key levers, both connected with said stop, said tabulating and margin release key levers being pivoted at different points, one being adapted to act on the other to produce a movement of the other opposite to its normal movement, a connection between the end of one lever and the escapement mechanism for throwing out the escapement mechanism when depressed, and a return spring connected to said arm adapted to aid in returning the parts to normal position.
- 50 15. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means connected with said second mentioned key lever whereby the step-by-step escapement of the machine is thrown out.
- 55 16. In a typewriting machine, in combination, a margin stop, a tabulator stop, a movable stop coöperative with said stops, means normally holding the movable stop in the path of the margin stop, a release key lever whereby the movable stop may be moved about a horizontal axis out of the path of travel of said margin stop, another key lever whereby the movable stop may be moved about the same axis into the path of the tabulator stop, and means permitting a movement of said movable stop about a vertical axis when engaged by the tabulator stop, and a carriage carrying marginal and tabulating stops, a coacting movable stop on the frame of the machine, tabulating and margin release key levers, both connected with said stop, said tabulating and margin release key levers being pivoted at different points, one being adapted to act on the other to produce a movement of the other opposite to its normal movement, a connection between the end of one lever and the escapement mechanism for throwing out the escapement mechanism when depressed, and a return spring connected to said arm adapted to aid in returning the parts to normal position.
- 60 17. In testimony whereof I affix my signature, in the presence of two witnesses.

NILS H. ANDERSON.
